INDUSTRIAL GAUGING HEAD FOR DETECTING MATERIAL PROPERTIES

Donald J. Tompos, Worthington, Ohio, assignor to Industrial Nucleonics Corporation, a corporation of Ohio

Filed June 13, 1958, Ser. No. 51,357

Term of patent 14 years

(Cl. D52—6)

Fig. 1

Fig. 2

Fig. 3

Fig. 4

FIG. 1 is a front perspective view of an industrial gauging head for detecting material properties on an enlarged scale showing my new design;

FIG. 2 is a top plan view of the gauging head shown in FIG. 1;

FIG. 3 is a side elevational view of the gauging head shown in FIG. 1; and

FIG. 4 is a front elevational view of the gauging head shown in FIG. 1.

I claim:

The ornamental design for an industrial gauging head for detecting material properties, as shown.
